DRIVE SYSTEM FOR TUNING ASSEMBLY

Hermann E. F. C. Lingenbrink, Hilltown, Pa., assignor to Philco Corporation, Philadelphia, Pa., a corporation of Pennsylvania

Filed Apr. 29, 1958, Ser. No. 731,831

1 Claim. (Cl. 74—10)

This invention relates to tuning means for broadcast receivers, particularly for small, portable receivers such as pocket radios. It is a general object of the invention to provide an instrument of the indicated type which can be accurately tuned by simple, manual operations.

Ordinary tuning knobs and shafts, adapted to the dimensions of the human hand and also to those of conventional receiver elements, are evidently too large for incorporation in such a small unit as can be carried in a pocket or held in one hand. If ordinary knobs, however, were simply miniaturized in proportion to the size of the cabinet or box, it would no longer be easy to adjust them accurately. Nevertheless a system of tuning elements is required, which elements must be moved relative to fixed points, and/or relative to one another, with considerable accuracy, often for instance with an accuracy exceeding that of the conventional adjustment of a small watch. A solution for this dilemma between smallness of construction and accuracy of adjustment forms an important object of this invention.

It has been found possible not only to solve this problem but in doing so to improve the tuning means also with respect to simplicity and economy, by minimizing the number and complexity of mechanical parts employed for inter-engagement of elements, for indication of approximate positions, and for related purposes. These latter improvements form added or independent features of the invention.

Briefly described the new construction, as illustrated herein, includes a receiver box of such small size that it can conveniently be held in one hand. According to one aspect of the invention the tuning system comprises relatively small wheel means—generally a pair of wheels—pivoted and generally disposed within the small receiver box, each wheel having tunable circuit means connected therewith and having a pair of wheel rim or segment areas exposed on opposite outer surfaces of the box, thereby allowing fine manual tuning by the relative small wheel means. According to another aspect of the invention two tuning wheels are directly interconnected by integral clutch means providing a controlled degree of relatively loose or lost-motion coupling therebetween; and the said wheels may additionally provide tuning indicator means on further integral portions of the wheels.

These and other features of the new construction will be described more fully in conjunction with the drawing, wherein:

Figure 1 is a perspective view of a preferred embodiment hereof and Figure 2 is a side view of said embodiment. Figure 3 is an enlarged fragmentary sectional view, taken along line 3—3 in Figure 2. Figure 4 is a partially exploded perspective view of some of the parts shown in Figure 3. Figure 5 is a section taken along line 5—5 in Figure 3. Figure 6 is a front view of the receiver box of Figure 1, partly broken away to show internal construction; and Figure 7 is a schematic wiring

2

diagram of the tuning system and of directly associated parts of the new receiver.

As shown in Figure 1, the pocket size receiver casing or box 10 has a pair of peripherally serrated or knurled tuning wheels 11, 12 therein, each of which has a segment thereof projecting beyond the front surface 13 of the box. A diametrically opposite segment of each wheel 11, 12 projects similarly from the back surface 14 of the box, as shown in Figures 2 and 3. On each surface of 10 the box, the so projecting portions of said wheels are separated from one another by a narrow strip 15 of the corresponding wall 13 or 14, (Figures 1 and 8).

Selector wheels 11, 12, as shown in Figure 6, preferably have indicia, such as numbers, associated therewith to indicate station frequencies or the like, and receptacle or casing 10 is shown in Figures 1 and 6 as providing for inspection of such indicia, by an aperture 16 in a top or end portion of the casing. The receiver is also shown in Figures 1 and 2 as having an on-off switch and volume control device 17 which utilizes an actuator wheel similar to wheels 11, 12; this latter wheel however being distinctively located and/or arranged and projecting only from one wall 13, remotely from the system of tuning wheels 11, 12. An electrical cord 18 connects the set to 25 a suitable earphone 19 with holder 20.

Referring now to Figures 3, 4 and 5, each selector wheel 11, 12 has loose or free-play coupling means 21 on one side thereof for the purpose of suitably interconnecting these wheels, while having rotary slide condenser means 22, 23 on the other side thereof. The mechanical construction of both condenser means 22, 23 may be substantially the same and only one of them has been shown in exploded form in Figure 4.

Each condenser includes a first segment carrier 24 of 35 insulating material, carrying a conductive segment 25. A central conductive pin 26 is electrically connected to this segment and is mechanically connected, by a square end portion as shown, with segment carrier 24 and also with wheel 11 or 12, see Figure 3. Each condenser also includes a thin dielectric wafer 27 of suitable ceramic or the like, which as shown in Figure 4 has a central aperture 28 for pin 26 and a conductive segment 29 suitably spaced from aperture 28. A resilient washer 30 is provided with a similar central aperture 31 and with an eccentric aperture 32; and pin 26 extends successively through apertures 28 and 31 and through a similar aperture 33 in an insulating bearing plate 34, and then into contact with a terminal clip 35. This clip engages an end portion 36 of the pin (Figure 3), thereby holding the bearing plate, 50 resilient washer, dielectric wafer and segment carrier 34, 30, 27 and 24 assembled. The assembly is secured to a wheel 11 or 12 by press fitting segment carrier 24 into the wheel; and due to the pivoting of elements 27, 30 and 34 on pin 26 the segments 25, 29 can be rotated relative 55 to one another, by rotating for instance wheel 12 relative to bearing plate 34, Figure 4.

A second connector clip 37, secured to bearing plate 34, has contact means 38 suitably indexed relative to aperture 32 in resilient washer 30; thus electrical voltages 60 can be provided across dielectric wafer 27. Similarly, electrical voltages can be provided across the dielectric wafer of the second condenser 23, which is mechanically of the same construction, while having independent electrical terminals 38, 39.

The loose coupling mechanism 21 interconnecting the two condensers 22, 23 is best illustrated in Figure 5 in conjunction with Figure 4. It will be seen that selector wheel 11 has jaw means 40, 41 integrally formed thereon opposite condenser 22, and wheel 12 has similar jaws 42, 43. Desirably each jaw constitutes an arcuate member 70 loosely fitting between the jaws of the opposite wheel, so

as to leave as many gaps 44 in coupling 21 as there are jaws; and the arrangement is desirably such that the several gaps have approximately uniform width. This is conveniently achieved by using wheels 11, 12 of substantially identical construction, each wheel having two diametrically opposite, arcuate jaws and each jaw covering for instance about 85 degrees of a complete circle.

Referring now to Figure 6 it will be seen that the loose coupling mechanism 21 and the associated condenser devices 22, 23 are disposed in an upper portion of the box 10. The bearing plate 34 of each tuning wheel 11, 12 is advantageously supported by a pair of holder members 45, 46 rigid with casing 10 and disposed within the same; one such member 46 can also be seen on each side of Figure 3. These holders desirably comprise channel members rigid with wall 13 and/or 14 and frictionally engaging edge portions of bearing plates 34. These latter plates desirably taper toward one end, as indicated in Figure 4, thus facilitating insertion in holders 45, 46. No accurate pivoting of wheels 11, 12 and associated parts is required, as it is desirable or even necessary to provide loose coupling; thus the entire wall and holder structure 13, 14, 45, 46 can be advantageously light, small and elastic.

The entire tuning wheel structure including the coupling and condenser means and bearing supports thereof is disposed in a recess 47 formed in a printed wiring panel 48; said panel having connecting means 49, 50, etc. for condenser terminals 35, 38, etc. The panel is also provided with associated circuit elements which are shown in Figures 6 and 7 and which comprise a first transformer or antenna unit 51; amplifier transformers 52, 53; a detector diode 54; amplifying transistors 55, 56; and associated circuit elements which require no detailed discussion herein. Suitable batteries 57 are used as a power source.

In order to operate the new device, the user of course starts by applying earphone 19 and by turning switch and volume control member 17 to "on" and to suitable volume. He then manipulates wheels 11 and 12 for the tuning in of a desired broadcast. For such manipulation the user can conveniently grasp the entire receptacle 10 in one hand and he may initially place the tips of forefinger and thumb of the same hand, on the exposed portions of one wheel 11 or 12, in the manner shown in Figure 2, although he may, if preferred, use two fingers of the other hand for this purpose. In either case the operation is very convenient, as the actual size of the unit is generally smaller than that of Figure 3; and at the same time the operation is accurate, as the two-sided gripping of each wheel, provided in this way, allows very gradual, minute shifting, particularly by virtue of the simultaneous abutment of each operating finger tip against the surface of receptacle 10.

As indicated by Figure 6, any substantial rotation of one tuning wheel 11 or 12, provided in this way, causes rotation of the other tuning wheel, which however remains free for adjustment relative to said one wheel, by virtue of the loose coupling between these wheels. The loose coupling is indicated in the circuit diagram of Figure 7 by broken line 21.

It will be understood from the latter diagram that initial, progressive, unidirectional rotation of one tuning condenser, 22 or 23, which results in generally similar rotation of the other tuning condenser, matches the primary or antenna coil of transformer 51 to the input of amplifier device 55 and, by loose coupling 21, partly matches the output of amplifier device 55 to the input of the second amplifier device 56, thereby providing a first maximum volume of output in earphone 19. A further increase in such output can then be obtained by progressively, unidirectionally moving only the other condenser to a slight extent, as is allowed by the loose mechanical coupling; this improves the matching of elements 55, 56.

There may follow a correction of the disturbance of elements 51, 55, caused by the fine matching of elements 55, 56. About two to four such consecutive movements of the condensers are generally required for adequately sharp tuning of a pocket radio; it being generally preferred first to move the two condensers conjointly, into the range of high volume output, and then to adjust them relative to one another within said range.

Some of these consecutive movements of the two condensers and wheels, mainly their adjusting movements relative to one another, involve very slight, delicate and accurate rotations of wheel 11 and/or 12; and such minute and precise motion is most readily achieved by the construction of the receiver casing, exposing two opposite segment areas of each tuning wheel. Displacements of the two wheels, relative to one another, can be detected and/or effected by this arrangement with considerably greater accuracy than is available when conventional tuning wheel designs and arrangements are used on the small scale which is here involved. The user of the new device can, as indicated by Figure 2, span the front and back walls of cabinet 10 between the thumb and a finger of one hand and can thereby frictionally engage any of the projecting segments of wheels 11 and 12. The width of the wheel-separating strip 15 (Figure 1) is, as shown, smaller than the width of a thumb or other finger. Thus the user can shift the tips of the fingers of the hand holding the cabinet from the segments of one wheel to those of the other. The manual adjustment, as already explained can be carried out with great accuracy as well as convenience, by virtue of the wheel segment arrangement as described. It can often be performed in merely a second or two.

Although only a single embodiment of the invention has been described, it should be understood that the details thereof are not to be construed as limitative of the invention, except insofar as is consistent with the scope of the following claim.

I claim:

40 In a pocket broadcast receiver: an enclosure which has front and rear walls, so closely spaced that one hand can span both of said walls; a receiver set in said enclosure; a tuning device comprising a pair of friction wheels, each being rigid and coaxial with one circuit tuner element which forms part of the receiver set, said wheels being coaxial one with the other, both being pivoted in said enclosure, each having a segmental portion projecting through said front wall and a segmental portion projecting through said rear wall, the segmental portions projecting through each of said walls being spaced apart not substantially more widely than the width of a finger; and a coupling, comprising jaw means on each of the two wheels, within said enclosure, each of said jaw means being rigidly, peripherally formed on one of said wheels and being adapted to engage and rotate the jaw means of the other wheel, subject to lost rotary motion, so that conjoint as well as relative rotation of said pair of tuner elements can be effected by each of two fingers of said one hand.
